UNITED STATES PATENT OFFICE.

JOHN MACKIN, OF BROOKLYN, NEW YORK.

BED.

1,131,147.

Specification of Letters Patent.

Patented Mar. 9, 1915.

Application filed November 30, 1912, Serial No. 734,369. Renewed July 23, 1914. Serial No. 852,764.

To all whom it may concern:

Be it known that I, JOHN MACKIN, a citizen of the United States, residing at Brooklyn, in the county of Kings and State of New York, have invented certain new and useful Improvements in Beds, of which the following is a specification.

This invention relates to improvements in beds and has for its object to provide a substitute for a mattress consisting of a resilient body supporting member adapted to give to the form and the movement of the body.

With the above and other objects in view which will be more fully explained in the following specification, I have invented the device illustrated in the accompanying drawings in which—

Figure 1 is a side elevation of my improved bed, Fig. 2 is a sectional view taken on line A—A of Fig. 3, and Fig. 3 is a bottom plan view of the device.

Like reference characters indicate like parts throughout the specification and in the several views in the drawings in which 1 indicates a rigid preferably metallic frame, to the corners of which are secured opposite bearing members 2 and 2', the upper ends of which project above said frame and rotatably mounted thereupon are rollers 3 and 4 to which are secured the ends 5 and 6 of the flexible member 7 which forms a body support. Also secured to said members 3 and 4 are downwardly projecting levers 8 to the lower ends of which are secured springs 9 and 9' which are connected by turn buckles 10, whereby the tension of the springs and consequently of the member 7 may be regulated according to the weight of the person sleeping thereon. The lever

members 8 are long enough to afford a perfect operation of the members 4 as the upper ends 11 of said levers curve almost entirely around said members 3 and 4, whereby said levers have perfect control of the 45 rollers 3 and 4. The members 2 and 2' have cut-away portions 12 to fit over an ordinary bedstead rail whereby the device may be held in proper position. The member 7 is formed with pockets 13 and 14 on its opposite ends in which rods 15 are located, said rods being adapted to hold the member 7 transversely stretched and the staples 16 connecting said rods to said rollers whereby the member 7 is held stretched until practically all of said staples are removed.

Having now described my invention that which I claim to be new and desire to procure by Letters Patent is:

A device of the kind described comprising 60 a substantially rectangular frame, four brackets secured at the corners of said frame and having bottom recesses, a transversely-extending roller mounted in said brackets at each end of said frame, coextensive rods of 65 lesser diameter than said rollers, a sheeting wound around a portion of each of said rollers and completely around said rods, staples straddling said rods and engaging said rollers to secure said sheeting to said rollers, a 70 plurality of levers carried by said rollers, and extensible springs carried by said levers and being connected to one another substantially in alinement with said frame.

In testimony whereof I affix my signature 75 in presence of two witnesses.

JOHN MACKIN.

Witnesses:

CHARLES LURCK,
LOUIS WOERNER.
